ALARM SYSTEM

Charles H. Sims, Kansas City, Mo., assignor to
 Associated Electric Laboratories, Inc., Chicago,
 Ill., a corporation of Delaware

Application October 26, 1936, Serial No. 107,586

12 Claims. (Cl. 179—5)

This invention relates in general to alarm signalling systems and more particularly to systems such as are used for transmitting fire, police, burglar, or other similar alarm calls, and the main object is to provide improved and simplified arrangements of the circuits and apparatus tending to economize in the cost and maintenance of the equipment.

Another object is to provide an alarm system in which all the lines are under constant supervision for unstandard conditions thereon and in which either a legitimate alarm signal or a line trouble alarm signal may be instantly detected. Other objects and certain novel features in connection therewith will be apparent from the description and the accompanying drawing illustrating by means of the usual schematic circuit diagram a preferred embodiment of the invention.

An alarm signalling station is indicated in full at A, it being understood that this is one of a plurality of similarly equipped stations in the system. Each station has an individual pair of line conductors extending to a central office where they terminate in the alarm receiving equipment B associated with that particular station. Also at the central office there is provided common control equipment C associated with all the equipment B, B', etc. The operator's cord circuit D at the central office is used for testing the lines and for talking purposes with any station. In the system illustrated it will be assumed that the equipment is to be used for making emergency calls from a subscriber's premises to the police.

At each alarm station A there is a non-locking key K and a handset telephone HS both connected to the line. This line is of the "closed circuit" type with current normally flowing over it in a path extending from ground through the winding of high resistance relay 10 in the associated equipment B at the central office; locking contacts 13 and operated armature spring 11 of alarm relay 10 which is normally held energized in this circuit; upper closed contacts of the telephone jack JK; line conductor 3; normally closed contacts 5 and 7 of alarm key K; normally closed contacts of the handset switchhook SW; line conductor 4; lower closed contacts of the telephone jack JK; through the trouble lamp TL to battery. The lamp TL receives insufficient current in this circuit to illuminate due to the resistance of alarm relay 10 which, however, as stated does energize. The resistor 8 connected to ground and the line 4 has a resistance of 10,000

ohms and therefore has no effect at this time. Its purpose will be explained hereinafter.

When an alarm is transmitted the subscriber momentarily presses the button or key on his premises. This action momentarily opens contacts 5 and 7 and also connects ground from contact spring 6 onto spring 5 and over the line conductor 3, resulting in the deenergization of alarm relay 10 which immediately deenergizes and restores its armatures, thereby opening its locking circuit at contact spring 13 so it cannot again energize when the key K is restored or repeatedly operated. At its contact springs 15 relay 10 connects ground from the closed contacts of the line trouble key LK to the winding of the common signal relay 25. This relay upon operating closes a circuit at its contacts for the gong G to audibly call the attention of the attendant at the central office that an alarm has been received. At contacts 16 alarm relay 10 closes the circuit from ground on the trouble key LK to the alarm lamp AL which illuminates and thereby indicates to the attendant that the station A has initiated the alarm. As a further result of the deenergization of alarm relay 10 it closes a circuit at its contacts 14 for slow acting relay 20 which slowly energizes and after a time opens its contacts 21. Before this occurs, however, the ground at contacts 14 is extended over contacts 21 through the winding of magnet TR to battery. This magnet TR is individual to the station A and may be in the form of any well known printing or recording magnet wherein its energization operates an armature to either print or mark the moving tape TP controlled in accordance with time mechanism, to make a permanent record at the central office of the station which sent in the alarm and also the time it was received. Relay 20 upon fully energizing opens the circuit of magnet TR at its contacts 21 and remains operated under control of alarm relay 10. The alarm signal has now been transmitted and the attendant at the central office is made aware of it by the illumination of alarm lamp AL, operation of gong G, and the marking on the recording tape TP, as pointed out.

After having received an alarm signal from a station such as A the central office attendant may require additional information or the person at the station may wish to further advise him. The attendant in this case takes up the plug PL of her cord circuit D and inserts it into the telephone jack JK associated with the station sending in the alarm. This connects the attendant's handset telephone HSP through the closed contacts of

key TK to the plug and jack contacts and the line conductors 3 and 4. At the station the removal of the handset telephone HS from the switchhook SW opens the switchhook contacts and connects the handset directly in circuit with the contacts 5 and 7 of alarm key K and the line conductors 3 and 4. Conversation can now take place with the talking potential supplied to both handset telephones through the windings of impedance coil 30.

To restore the equipment after it has been operated and also to check whether the alarm is a legitimate one and not caused by trouble on the line, the attendant at the central office momentarily operates the common reset key R thereby closing contacts 23 and connecting battery potential through a low resistance, through the new closed contacts 12 and 13 of alarm relay 10 and the winding of that relay to ground. As a result alarm relay 10 is again energized and maintained operated over its locking contacts 11 and 13 and over the line conductors 3 and 4 through the station A and in series with the lamp TL. At contacts 14 the circuit of relay 20 is opened, at contacts 15 the circuit of signal relay 25 is opened to silence the gong G, and at contacts 16 the energizing circuit of alarm lamp AL is disconnected. The equipment is now at normal again ready to receive other alarm signals. After receiving an alarm signal the attendant may operate the key AK in her cord circuit D and thereby connect her handset telephone HSP to the police trunk and provide the necessary instructions regarding the location of the alarm. The key AK disconnects the lower winding of impedance 30, as the talking battery in this instance is fed over the trunk line from the police exchange equipment.

Assume now that an accidental ground occurred somewhere along the line conductors 3 and 4 extending from the station to the office or anywhere within the station or the office; the foreign ground potential passes over the line conductors and results in the direct illumination of the trouble lamp TL to call the attendant's attention to the trouble. As a further result alarm relay 10 deenergizes and by restoring its armature springs effects the registration of the trouble on the time recorder magnet, sounds the gong G, and illuminates the alarm lamp AL. The attendant then operates the line trouble key LK which at its normally open contacts connects direct ground potential to the trouble lamp TL to maintain it illuminated and at the normally closed contacts of the key disconnects the ground from the circuit of alarm lamp AL to extinguish it and also to restore relay 25 to silence the gong G. The circuits remain in this condition until the trouble has been cleared up after which the trouble key LK is restored and the reset key R operated to energize relay 10 over the line circuit in series with lamp TL. From the foregoing it will be apparent that a momentary ground such as applied by the alarm key will initiate an alarm signal, while a "permanent" ground will result in a trouble alarm signal being transmitted.

In case the normally closed line circuit is accidentally opened but not grounded, relay 10 deenergizes and operates the alarm lamp AL, gong G, and also registers the signal on the magnet TR. The attendant will not be aware that this is a case of trouble and not a legitimate alarm signal until the reset key R is operated momentarily when he will observe that the alarm lamp AL will remain illuminated instead of going out.

This is due to the fact that relay 10 cannot again remain energized over the line loop circuit after it is initially energized by the reset key R. The attendant thereupon operates the line trouble key LK to light the trouble lamp TL until the trouble is cleared.

Should it occur that the line conductors 3 and 4 be short circuited this would not automatically reveal itself as a source of trouble at the central office, because the contact springs 5 and 7 at the key K are normally closed. A regular alarm can, however, be transmitted to the central office because the ground on contact spring 6 is extended over both line conductors resulting in the illumination of trouble lamp TL and the short-circuiting of alarm relay 10 to bring in the alarm signal, as pointed out. The illumination of trouble lamp TL indicates a case of trouble on the line and the attendant proceeds to test the line in the manner to be hereinafter pointed out.

The attendant as part of his duties will as a matter of routine periodically test the alarm receiving equipment B and for this purpose he is provided with the test key T. This key is conveniently made common to not more than five alarm lines so that the five equipments can be tested and observed simultaneously. Operation of test key T connects direct ground potential through its contacts 22 to armature 11 and one side of the winding of alarm relay 10, thereby short-circuiting the same and deenergizing it to bring in the regular alarm signals, the same as if a regular alarm had been received. In addition the same ground potential from test key T extends over the line conductor and as the resistance of relay 10 is no longer included in this circuit the trouble lamp TL is illuminated. To restore the equipment to normal again the reset key R is actuated to operate relay 10 as has been previously pointed out. This constitutes a test of the operativeness of the alarm equipment.

When a case of trouble has occurred on an alarm line the attendant, as has been pointed out, operates the line trouble key LK which maintains trouble lamp TL illuminated and disconnects the regular alarm signals AL and G. The line in trouble is now prepared for further accurate testing by the attendant who first takes the cord circuit into use by inserting plug PL into the jack JK of the line and thereby cause the jack springs to disconnect the alarm receiving equipment B from the line. The test key TK is then operated to disconnect the attendant's handset HSP and the impedance 30. The approximate normal line resistance of the alarm lines has been predetermined with the provision of the high resistance 8 connected to ground at each alarm station and accurate tests of the line conditions may be made by the voltmeter in the cord circuit D. The testing means comprises the 48-volt exchange battery, the voltmeter having a scale reading up to 100 volts and an internal resistance of 100,000 ohms, and the keys VK, NK, and PK. In measuring the resistance of an alarm line the well known formula is used whereby the line resistance in ohms is equal to the product of the voltmeter resistance winding and the quotient obtained by dividing the difference between the voltage of the exchange battery and the voltmeter reading by that reading as expressed by the formula:

$$X = \frac{E - E'}{E'} R$$

in which X is the line resistance to be measured.

E the exchange battery voltage, E' the voltmeter reading, and R the resistance of the voltmeter. Tests are made for "permanent" grounds, open circuiting and foreign potential.

5 To test for the presence of ground potential on the positive line conductor 4 the key PK is held operated and thereby connects the negative battery potential from the closed contacts of key VK through the voltmeter, lower contacts of operated 10 key TK and out over the line conductor 4, and through high resistance 8 to ground. The deflection of the voltmeter needle indicates the voltage drop on the line conductor 4 and by applying the formula as pointed out, the line resistance to 15 ground may be obtained. If there is no deflection an open circuit in the line conductor 4 or a ground return is indicated. The same test is made to the negative line conductor 3, but in this case the key NK is operated instead of 20 key PK.

In the case of a short circuit across the line conductors 3 and 4 the deflection of the voltmeter needle will indicate this because of the reduction of the predetermined known resistance of the line 25 circuit through the high resistance 8 to ground.

Another test is made for the presence of a foreign potential on the line conductors. To make this test the key VK is operated and then the key PK. Ground is thereby connected 30 through resistance 17 and the now closed contacts of key VK to the positive (+) terminal of the voltmeter. The negative (-) terminal is connected through operated contacts of key VK, PK, and TK to the line conductor 4. Deflection 35 of the voltmeter needle indicates a grounded negative potential on the positive line conductor 4 and if the deflection of the needle is off the scale a grounded positive potential is indicated. The same test is made to the negative line conductor 40 3 but in this instance the key NK is operated instead of key PK. The removal of plug PL from the jack JK and restoration of key LK places the circuits again in normal condition provided, of course, that the line trouble has been cleared 45 up.

The invention having been described, what is considered to be new and is desired to be protected by Letters Patent will be set forth in the following claims:

50 What is claimed is:

1. In an alarm system, an alarm station, a central office, a line circuit extending between said station and said office and comprising a pair of line conductors, a key at said alarm station connected to said line conductors, a relay at said central office connected to one of said line conductors, a trouble signal connected to the other of said line conductors, means responsive to the operation of said key for operating said relay but not said trouble signal, and an alarm signal operative in response to the operation of said relay.

2. In an alarm system, an alarm station, a pair of line conductors extending to said alarm station, a key at said station connected to said line conductors, a relay at which one of said line conductors terminates, a trouble signal at which the other of said line conductors terminates, means for normally energizing said relay over a series circuit including said line conductors, said key and said trouble signal, means responsive to the operation of said key for opening the line conductors to deenergize said relay, and an alarm signal operated in response to the deenergization of said relay.

3. In an alarm system, an alarm station, a pair of line conductors extending to said station, a trouble signal and an alarm relay at which said line conductors respectively terminate, a key at said station connected to said line conductors, 5 said relay being normally energized over a series circuit including said key, said alarm relay, said conductors and said trouble signal, said alarm relay being operated when energized over said series circuit, said trouble signal remaining inactive when energized over said circuit, means responsive to the operation of said key for interrupting said normally closed series circuit to deenergize said alarm relay, an alarm signal operated in response to the deenergization of 10 said alarm relay, and means for reoperating said alarm relay over a circuit excluding said line conductors.

4. In an alarm system, an alarm key, an alarm relay and a trouble signal, a normally closed 20 line circuit including said alarm key, said alarm relay and said trouble signal all connected in series, locking contacts in said alarm relay through which it is normally held energized over the line circuit, means responsive to the operation of said alarm key for opening said line circuit to cause the deenergization of said alarm relay and the opening of said locking contacts, an alarm signal operated in response to the deenergization of said alarm relay, and means for 30 reenergizing said alarm relay over a circuit independently of said line circuit and including said locking contacts.

5. In an alarm system, a normally closed line circuit, an alarm station including thereat an 35 alarm key connected to said line circuit, a trouble signal and an alarm relay connected in series and included in said line circuit, said alarm relay normally being operated when energized over said circuit, said trouble signal remaining inactive 40 when energized over said circuit, means controlled by said alarm key for momentarily opening said line circuit to deenergize said alarm relay, an alarm signal operated in response to the deenergization of said alarm relay, and means operative 45 when a fault occurs in said line circuit for deenergizing said line relay and for operating said trouble signal.

6. In an alarm system, a line circuit, an alarm relay and a trouble signal connected in series 50 and included in said line circuit, said alarm relay normally energized over said line circuit, said alarm signal remaining inactive when energized over said circuit, an alarm key for opening said line circuit to deenergize said alarm relay when an alarm is transmitted, an alarm signal operated in response to the deenergization of said alarm relay, said alarm key also being operative to ground said line circuit to deenergize said alarm relay and operate said trouble signal in 55 case the line is short-circuited at the time an alarm is transmitted, said alarm relay being automatically deenergized in case the line circuit is opened or grounded, means for reoperating said alarm relay after an alarm has been transmitted, said alarm relay failing to remain operated in case the line is grounded or open, and means for operating said trouble signal to indicate the case of trouble on the line until it is corrected and for disconnecting said alarm signal. 60

7. In an alarm system, a line circuit, an alarm relay including a set of locking contacts connected in said circuit, means for normally energizing said alarm relay over said line circuit, an alarm key included in said line circuit for 65 70 75

- transmitting an alarm, means responsive to the operation of said alarm key for deenergizing said alarm relay, means responsive to the deenergization of the alarm relay for giving an indication of said alarm and for opening said locking contacts, a reset key connected to said locking contacts, the operation of said reset key being effective to reenergize said alarm relay through said locking contacts over a circuit independent of said line circuit, and a testing key connected to said locking contacts, said testing key being operative to deenergize said alarm relay, thereby to simulate the sending of an alarm independent of said line circuit.
8. In an alarm system, a line circuit, an alarm relay, an alarm signal controlled by said alarm relay, a trouble signal connected in series with said alarm relay and included in said line circuit, said alarm relay being operated when energized over said series circuit, said trouble signal remaining inactive when energized over said circuit, an alarm key in said line circuit operative to deenergize said alarm relay, thereby to cause the operation of said alarm signal, a reset key operative to reenergize said alarm relay, said trouble signal being operative when said line circuit is grounded, said alarm relay being deenergized when the said line circuit is grounded, and a line trouble key operative to maintain said trouble signal operated and to disconnect said alarm signal until the ground is removed from said line circuit.
9. In an alarm system, a line circuit, an alarm relay normally energized over said line circuit, means for transmitting an alarm by opening said line circuit to deenergize said alarm relay, an alarm signal operated in response to the deenergization of said alarm relay, a slow acting relay operated in response to the deenergization of said alarm relay, registering means for recording an alarm, and means controlled jointly by said slow acting relay and said alarm relay for operating said registering means.
10. In an alarm system, a line circuit, a line relay normally energized over said line circuit,
- means responsive to the transmission of an alarm over said line circuit for deenergizing said line relay to give an indication of said alarm, a slow-acting relay operated in response to the deenergization of said alarm relay, registration means for recording the alarm transmitted, and a series circuit for operating said registration means extending through contacts of said alarm and slow-acting relays, said circuit being closed in response to the deenergization of said alarm relay and before said slow-acting relay fully energizes.
11. In an alarm system, a central office; a trouble signal, an alarm relay and an alarm signal all located at said office; said alarm signal being operative in response to the operation of said alarm relay; an alarm station; a switch at said station; and circuits interconnecting said trouble signal, said alarm relay, said alarm signal and said switch; said circuits being so connected and arranged that said alarm signal is normally inactive and is operated in response to the operation of said key, said trouble signal is normally partially energized and remains only partially energized upon operation of said key, and said trouble signal operates upon the occurrence of a fault in said circuits.
12. An alarm system, an alarm station, a central office, a pair of line conductors extending between said central office and said station, a relay and a trouble signal at said office, a key at said station, said relay and said signal normally being energized over a circuit including said line conductors, said key, said relay and said signal, said relay being operated when energized over said series circuit, said trouble signal remaining inactive when energized over said circuit and being operative when a fault occurs in said circuit, means responsible to the operation of said key for interrupting said circuit to deenergize said relay, an alarm signal at said office operated in response to the deenergization of said alarm relay, and operator control means at said office for reenergizing said relay.
